(57) CLAIM

I claim the ornamental design for a portable phone, as shown and described.

DESCRIPTION

FIG. 1 is a front perspective view of a portable phone;

FIG. 2 is a rear perspective view thereof;

FIG. 3 is a front elevation view thereof;

FIG. 4 is a right side elevation view thereof;

FIG. 5 is a left side elevation view thereof;

FIG. 6 is a rear elevation view thereof;

FIG. 7 is a top plan view thereof; and,

FIG. 8 is a bottom plan view thereof.

The broken line showing of environmental features is for illustrative purposes only and forms no part of the claimed design.
